UNITED STATES PATENT OFFICE.

LAURA M. MEYERS, OF ELMHURST, NEW YORK.

CAN-CLOSURE.

1,220,873.

Specification of Letters Patent.

Patented Mar. 27, 1917.

Application filed September 13, 1916. Serial No. 119,898.

To all whom it may concern:

Be it known that I, LAURA M. MEYERS, a citizen of the United States, residing at Elmhurst, in the county of Queens and 5 State of New York, have invented certain new and useful Improvements in Can-Closures, of which the following is a specification, reference being had therein to the accompanying drawing.

10 My invention relates to improvements in can closures, and more particularly relates to an improved attaching means for the cover of a garbage can.

15 In the ordinary type of garbage can having the usual flange cover top whenever the can is tipped over the top is dislodged and the garbage in the can spilled, making the can unfit as a sanitary container.

20 The flange cover top is also easily removed by wind or by cats and dogs, and the contents of the can dragged or spilled on the ground. The present improvement provides means for holding the top on the can and preventing its dislodgment until 25 the same is removed for placing garbage in the can or for emptying it.

Another object of the present improvement is to provide a holding means for the cover which is simple, and cheap to manufacture.

30 Other objects and advantages of the present improvement will be set forth in the following description and drawings, in which—

35 Figure 1 is a vertical sectional view through the can and cover showing the locking means in operation.

Fig. 2 is a disassembled perspective view 40 of the can and cover showing the interlocking means carried by them.

Referring now to the drawings in detail, in which like reference numerals designate similar parts throughout the several figures, 1 represents the can of the usual type now 45 employed in garbage containers, and having on its upper edge a plurality of outwardly turned ears 2, spaced around the periphery thereof forming openings 3, between the ears. The said ears 2 may be 50 made integral with the can body or secured thereto by means of solder or rivets. The can cover comprises a body portion 4, having the usual depending flange 5, the diameter of the cover being considerably greater 55 than the diameter of the can, as is shown in Fig. 1. A plate 6 is secured to the inside

of the top of the cover 4, by means of solder or rivets, the edge 7 of the plate 6 being bent a slight distance below the top of the cover 4. The said edge 7 is doubled upon 60 itself at 8.

In applying the cover 4 to the can 1, the flanges 9 are passed down through the openings 3, between the ears 2, on the can body, the openings 9' in the plate passing over 65 the ears 2. The cover is then turned by means of the handle 10 so that the ears 2 pass between the flanges 9 and the downwardly bent portion 7 of the plate 6. The ears 2 are then secured in place and the 70 cover cannot be removed from the can body until the cover is again turned and the ears 2 are disengaged from the flanges 9. Due to the fact that the edge 7 of the plate is bent down, a spring action is caused on 75 the flanges 9 and keeps them in close engagement with the ears 2. Frictional engagement between the ears 2 and flanges 9 is augmented by bending the ears 2 downwardly to a slight degree, as is shown in 80 Fig. 2.

Attention is directed to the fact that the space between the wall 1 of the can and the flange 5 of the cover 4 is sufficient to permit the ears 2 to extend between them and cover 85 the ears and the flanges 9.

Due to the construction of the cover attaching means any can may be readily equipped with a locking cover by securing a plate 6 and ears 2 to the cover and can 90 respectively.

Having thus described my invention, what I claim and desire to secure by Letters Patent is—

1. A garbage can comprising a body portion having a plurality of ears carried by the upper edge thereof, a cover, a plate carried by the under side thereof, the edge of the plate bent downwardly from the cover having a plurality of inwardly extending 95 portions parallel with the plate forming flanges, the said flanges adapted to interlock with the ears carried by the can body portion.

2. A garbage can comprising a body portion having a plurality of outwardly extending and downwardly inclined ears carried by the upper edge thereof, a cover, a plate carried by the cover, the edge of the plate bent downwardly from the cover and 105 having a plurality of inwardly extending 110 portions parallel with the plate forming

flanges spaced apart from the plate, the said flanges adapted to interlock with the ears on the can body and frictionally hold them between the said flanges and the 5 downwardly bent edges of the plate.

3. A garbage can comprising a body portion having a plurality of outwardly extending and downwardly inclined ears carried by the upper edge thereof, a cover of 10 a greater diameter than the can and having a depending flange surrounding the top of the can and covering the ears carried thereby, a plate carried by the cover, the edges of the plate bent downwardly from

the cover and having a plurality of inwardly extending portions parallel with the plate forming flanges spaced apart from the plate, the said flanges adapted to interlock with the ears on the can body and frictionally hold them between the said 20 flanges and the downwardly bent edges of the plate.

In testimony whereof I hereunto affix my signature in the presence of two witnesses.

LAURA M. MEYERS.
